[57] CLAIM

The ornamental design for a bulk food dispenser, as shown and described.

DESCRIPTION

FIG. 1 is a front elevational view of a bulk food dispenser showing my new design;

FIG. 2 is a right side elevational view thereof; the left side elevational view being a mirror image thereof;

FIG. 3 is a rear elevational view thereof in an open position;

FIG. 4 is a bottom plan view thereof;

FIG. 5 is a top plan view thereof in an open position; and,

FIG. 6 is a perspective view thereof.
